JOSEPH E. McCANLESS, OF WAXAHACHIE, TEXAS.

CULTIVATOR-HOPPLE.

1,085,623.

Specification of Letters Patent.

Patented Feb. 3, 1914.

Application filed April 8, 1913. Serial No. 758,604.

To all whom it may concern:

Be it known that I, JOSEPH E. McCANLESS, a citizen of the United States, residing at Waxahachie, in the county of Ellis and State of Texas, have invented certain new and useful Improvements in Cultivator-Hopplles, of which the following is a specification.

My invention relates to cultivator hopplles, and its object is to provide a cultivator hopple so constructed that the lever controlling the same may be angularly adjusted about an axis parallel with the cultivator beams to displace said beams to or from each other, and may be also angularly adjusted about an axis transverse of said beams to bring the lever to or from the operator. Such a hopple makes it possible for the operator to swing the controlling lever close to his body so as to put forth his strength to better effect in adjusting the cultivator beams to or from each other, and when the beams are properly spaced, the lever may be swung away from the operator so as not to impede him.

A further object of my invention is to provide a device of the character described that will be strong, durable, simple and efficient and comparatively easy to construct and also one that will not be likely to get out of working order.

With these and various other objects in view my invention has relation to certain novel features of the construction and operation 35 an example of which is described in the following specification and illustrated in the accompanying drawing.

In this drawing, my novel hopple is shown adapted to adjust a pair of cultivator beams upon which it is mounted, the cultivator frame being omitted as forming no part of my invention.

Referring now more particularly to the drawing, the reference character 1 is applied to a pair of cultivator beams provided at their forward ends with the usual pivot heads 2, and serving in the usual manner to mount plow standards 3. Upon the middle portion of one of the beams, there is clamped 45 a bracket member 4 provided with two integral upstanding lugs 5. A U-bolt 6 constitutes the means for clamping said bracket upon the correlated beam. Upon the other beam, at a point opposite to the bracket 4, there is mounted a bracket 7, held in place 55 by a clamping U-bolt 8 and bifurcated at

its upper extremity. The function of the bracket 7 will be made clear hereinafter. The two lugs 5 serve to mount a bolt 9 transverse of the cultivator beams, which bolt is screw threaded in said lug, and is provided upon its inner end with a bifurcated head 10. Between the furcations of said head, there is pivoted the lower extremity of a lever 11, the pivotal axis of said lever being normally parallel with the beams. Upon the bracket 4, between the lugs 5, there is centrally pivoted a horizontal semicircular bracket 12, a pivotal support for said bracket being formed by one of the arms of the U-bolt 6. The extremities of the bracket 12 are in horizontal alinement with the pivoted lower end of the lever 11, and upon said extremities are respectively pivoted the ends of a semicircular rack 13, lying normally in a vertical plane with its middle portion adjacent to the lower portion of the lever. Since the bolts 14 which pivot the rack 13 upon the brackets 12 are alined with the bolt which pivotally supports the lever 11, 80 said lever and said rack are adapted to swing together about the same pivotal axis, which axis is normally parallel with the cultivator beams. It is apparent that the lever 11 is also adapted to undergo an angular 85 displacement about the axis established by the bolt 9, said bolt being rocked during such displacement. The rack 13 will remain stationary when the lever 11 is being subjected to the angular displacement last 90 mentioned. The usual spring pressed plunger is mounted upon the lever 11 to engage between any two teeth of the rack 13 and thereby hold the lever 11 in various positions of angular adjustment about the axis 95 formed by the bolt 9. In order to hold the central portion of the rack 13 closely adjacent to the lever 11, so that they must rotate as a unit about an axis passing through the bolts 14, a small curved bracket 15 is 100 mounted upon the lever just beneath the central portion of said rack and is made to pass beneath said central portion bending up against the outer face thereof. Thus said rack must share in any angular displacement to which the lever 11 is subjected 105 about an axis through the bolts 14.

A short space above the rack 13, another rack 16 transverse with the rack 13 is rigidly mounted, one end portion of the rack 110 16 being bent into a substantially radial relation with the body portion of said rack

and being pivotally mounted upon the lever 11 as indicated at 16^a. Upon the other end portion of said rack a screw threaded arm 17 is formed, which arm projects horizontally in the direction of the beam upon which the bracket 7 is mounted. The arm 17 has a threaded engagement with a collar 17^a integrally formed upon the lower extremity of a curved bar 18 which projects upwardly at an inclination toward the left hand side of the cultivator. A bolt 19 extending horizontally toward the left side of the machine is formed upon the upper end of the bar 18, and has threaded engagement 15 with a pair of lugs 20 formed upon the upper extremity of a bar 21. The last named bar extends downwardly at an inclination to the left hand side of the machine and has formed upon its lower end a horizontal arm 20 22, which is received between the furcations of the bracket 7 and is provided with a plurality of bolt holes 23 through any one of which may be passed a pivot bolt mounted in said bracket 7. Upon the lever 11, there 25 is mounted the usual spring pressed plunger to engage between any two teeth of the rack 16 for the purpose of holding said lever adjusted in any position of angular displacement about an axis passing through the 30 bolts 14.

It is clear from the foregoing description that the lever 11 is adapted to undergo two independent angular adjustments about axes transverse with each other, respectively 35 passing through the bolt 9 and through the bolts 14. When the plunger which is correlated with the rack 16 has engagement with said rack, the cultivator beams are held in a fixed spaced relation, since the lever 40 11 may not under such conditions swing about its lower pivotal axis. It is also apparent that when the plunger correlated with the rack 16 has engagement with said rack, the lever 11 is restricted from angular 45 displacement about the axis formed by the bolt 9, the lever will be free to swing forwardly or rearwardly, the bolt 9 forming a rocking pivot and the member 18 swinging about its pivoted extremities. When the 50 lever 11 after having been displaced to a considerable extent either forwardly or rearwardly of the machine, is subjected to a displacement toward either side of the machine to vary the distance between the beams 1, 55 a laterally acting pressure will come upon an end portion of the rack 14 and will be transmitted to the semicircular bracket 12 causing the same to rock about its pivoted central point. It is to be understood that 60 when the lever 11 is swung about the pivot formed within the head 10, there will be a relative displacement between the said lever and the rack 16, the latter rocking about its pivoted extremity 16^a. According as the 65 bolt passing through the holes 23 and the

arms 22 is mounted in the outermost or innermost hole, the spaced relation of the plow beams will be greater or less.

The invention is presented as including all such modifications and changes as properly come within the scope of the following claims.

What I claim is:

1. A cultivator hopple comprising a member rotatably mounted upon one of the cultivator beams, the axis of rotation of said member being horizontal and transverse of the correlated beam, a lever pivotally mounted upon said member, the pivotal axis of the lever being transverse with the axis 75 of rotation of said member, means correlated with said lever for holding the same adjusted in various positions of angular displacement about the axis of rotation of said member, a toothed rack pivotally mounted upon said lever in a transverse relation with the beams, means mounted upon the lever for engaging said rack to hold the lever in a rigid relation therewith, a connection between said rack and the other cultivator 80 beam, said connection being such that the lever is permitted to swing about its pivotal connection with said member only when the rack is free from the said means for engaging the same, and is permitted to 85 swing about the axis formed by said member when freed from the means provided to prevent such displacement.

2. A cultivator hopple, comprising a member rotatably mounted upon one of the 100 cultivator beams, the axis of rotation of said member being horizontal and transverse of the correlated beam, a lever pivotally mounted upon said member, the pivotal axis of the lever being transverse with the 105 axis of rotation of said member, means correlated with said lever for holding the same adjusted in various positions of angular displacement about the axis of rotation of said member, a toothed rack pivotally mounted upon said lever in a transverse relation with the beams, means mounted upon the lever for engaging said rack to hold the lever in a rigid relation therewith, a bar pivotally mounted upon the other cultivator beam, the mounting being such that the said bar 110 may swing transverse of the beam but not longitudinally thereof, and a bar establishing a swinging connection between the upper end of the last named bar and said rack, said bar being adjusted to swing only toward the front or rear of the machine.

3. A cultivator hopple, comprising a pair of brackets respectively mounted upon the 115 cultivator beams in opposite relation, a member rotatably mounted upon one of the cultivator beams, the axis of rotation of said member being horizontal and transverse of the correlated beams, a lever pivotally mounted upon said member, the pivotal 120

12b

120

125

axis of the lever being transverse with the axis of rotation of said member, a semi-circular bracket centrally pivoted upon the bracket carrying the rotatable member, the 5 pivotal axis being vertical, a semicircular rack having its extremities respectively pivoted upon the extremities of said semicircular bracket, the pivotal axis being normally horizontal and parallel with the 10 beams, means holding the central portion of said rack constantly adjacent to the lower portion of the lever, means carried by the lever for engaging said rack to hold the lever in a rigid relation therewith, a toothed 15 rack pivotally mounted upon the lever above the first named rack and in a transverse relation with the beams, means mounted upon the lever for engaging said rack to

hold the lever in a rigid relation therewith, a connection between said rack and the other 20 cultivator beam, said connection being such that the lever is permitted to swing about its pivotal connection with said member only when the rack is free from the said means for engaging the same, and is permitted to 25 swing about the axis formed by said member, when freed from the means provided to prevent such displacement.

In testimony whereof I have signed my name to this specification in the presence of 30 two subscribing witnesses.

JOSEPH E. McCANLESS.
